UNITED STATES PATENT OFFICE.

FREDELLIA H. MOYER, OF CANTON, OHIO.

STEEL JOIST.

Application filed September 29, 1926. Serial No. 138,404.

The invention relates to structural members made of steel and the like, for use in buildings as joists, beams, girders or rafters.

The object of the improvement is to provide a trussed member which may be formed of ordinary standard steel bars or structural shapes in common use, comprising spaced chord members connected by alternately bent web bars, the lower chord being supported at each end by an integral hanger in the form of a stirrup connected to the end portions of the upper chord forming beam ends upon the joist.

An embodiment of the invention is illustrated in the accompanying drawings, forming part hereof, in which

Figure 1 is a side elevation of a portion of one of the improved joists showing the chord members formed of T-bars;

Fig. 2, a perspective view of the same, and

Fig. 3, a perspective view of a portion of a joist, the chord members of which are formed of spaced round bars.

Similar numerals refer to similar parts throughout the drawings.

Referring first to Figs. 1 and 2 of the drawings, a joist is shown in which the top chord 1 and bottom chord 2 are of cross sectional T-shape having their ribs 3 in vertical alignment with, and disposed toward each other.

The chord members 1 and 2 are parallel with each other throughout their lengths, the lower chord 2 terminating at its ends at points spaced from the ends of the top chord 1.

A bar 4 bent into zig-zag form is located between the spaced chord members, having its alternate bends connected to the ribs of the chord members as indicated at 5, by welding or the like, forming a web element for the joist.

The ends of this web bar are extended upward vertically from the end portions of the lower chord and attached to the rib of the upper chord as indicated at 6, by welding the inturned ends of the bar to the rib of the top chord.

For the purpose of supporting the ends of the lower chord from the upper chord, a

hanger 7, in the form of a stirrup or U-shape, is connected to the upper chord as by the outturned ends 8 which may be welded to the under surface of the top chord upon each side of the rib 3 thereof.

This hanger is preferably formed of a bar having a diameter substantially equal to the depth of the rib 3, thus permitting the end portions 8 of the hanger and the rib 3 of the top chord to rest upon a beam or the like as indicated at 9, this extension of the top chord with the outturned ends 8 of the hanger forming a beam end upon the joist.

This hanger may be welded to the lower chord also, thus providing an attached hanger which supports the lower chord from the upper chord and also from the support such as the beam 9, upon which the beam ends of the improved joist rest.

A modification of the invention is shown in Fig. 3 in which the upper chord is formed of the spaced round bars 1^a and the lower chord of similar bars 2^a of less length than the upper chord. The web 4^a and hanger 7^a may be the same as that shown in Figs 1 and 2, the outturned ends 8^a of the hanger being welded to the beam ends of the top chord bars 1^a, a short bar or plug 10 being provided between the spaced chord bars and end portions 8^a of the hanger and being welded to all of said parts to form a solid rigid beam end upon the joist.

A bar joist is thus produced formed of rolled shapes cut to the desired lengths and connected by the zig-zag web bar of proper length, the hangers being welded to the end portions of the structure, forming beam ends without the necessity of bending the lower chord member upward and attaching it to the upper chord.

I claim:

1. In a structural member including upper and lower chord bars and an intervening zig-zag web bar secured at its bends as by welding to the chord bars U-shaped hangers connected to the upper chord bar extending below and supporting the ends of the lower chord bar.
2. In a structural member including upper and lower chord bars and an intervening

zig-zag web bar secured at its bends as by welding to the chord bars, **U**-shaped hangers connected to the upper chord bar extending below and supporting the ends of the lower chord bar, the upper ends of the hanger being outturned and forming, in conjunction with the ends of the upper chord, beam ends for the joist.

3. In a structural member including upper and lower **T**-shaped chord bars and an intervening zig-zag web bar secured at its bends as by welding to the chord bars, **U**-shaped hangers connected to the upper chord bar extending below and supporting the ends of the lower chord bar.

4. In a structural member including upper and lower chord bars, the upper bar being **T**-shaped, and an intervening zig-zag web bar secured at its bends as by welding to the chord bars, **U**-shaped hangers connected to the upper chord bar extending below and supporting the ends of the lower chord bar.

5. In a structural member including upper and lower chord bars and an intervening zig-zag web bar secured at its bends as by welding to the chord bars, the ends of the web bar being bent up vertically from the lower chord and connected to the upper chord, **U**-shaped hangers connected to the upper chord bar extending below and supporting the ends of the lower chord bar.

6. In a structural member including spaced upper and lower chord bars, the upper chord bar being of greater length than the lower, an intervening zig-zag web bar secured at its bends as by welding to the chord bars, **U**-shaped hangers having outturned ends connected to the outer end portions of the upper chord bar extending below and supporting the ends of the lower chord bar.

7. In a structural member including an upper **T**-shaped chord bar, a lower chord bar of less length than the upper bar and spaced therefrom, an intervening zig-zag web bar secured at its bends as by welding to the chord bars, **U**-shaped hangers extending below and supporting the ends of the lower chord bar and having outturned upper ends secured to the end portions of the upper chord bar and forming beam ends upon the structural member.

8. In a structural member including an upper **T**-shaped chord bar, a lower chord bar of less length than the upper bar and spaced therefrom, an intervening zig-zag web bar secured at its bends as by welding to the chord bars, **U**-shaped hangers extending below and supporting the ends of the lower chord bar and having outturned upper ends secured to the end portions of the upper chord bar, the outturned ends of said hangers being of substantially the same thickness as the rib of the **T**-bar and forming beam ends upon the structural member.

9. In a structural member including upper

and lower chord bars and an intervening zig-zag web bar extending throughout the length of the structural member and secured at its bends, as by welding, to the chord bars, and **U**-shaped hangers connected to the upper chord bar extending below and supporting the ends of the lower chord bar.

In testimony that I claim the above, I have hereunto subscribed my name.
